ABSTRACT OF THE DISCLOSURE

Apparatus for lifting cops from spindles. The cop manipulating apparatus is mounted on a carriage which travels at a constant speed past the spindles on which the cops are mounted, a cop engaging member mounted on the carriage grips a cop and simultaneously the engaging member is lifted to raise the cop off the spindle and is moved in a direction opposite the direction of movement of the carriage to eliminate relative movement of the spindle and the engaging member.

The present invention relates to a process and to apparatus for the continuous replacement of full cops with empty cops, i.e. empty cop tubes, on, for example, ring spinning machines and ring twisting machines, by means of a doffing apparatus which can travel along on the machine on rails at constant speed and which can be equipped with one container for feeding the empty cops and one for doffed cops, the cops being doffed successively one at a time by means of a grasping device.

Cop doffing apparatus disposed on a carriage traveling along the machine at constant speed have become known in various forms. These cop doffers which move continuously along the machine have the advantage in general, over cop doffers which move step-wise along the machine, of a simpler driving means. Another advantage of such apparatus consists in the fact that the entire mass of the doffing apparatus together with the magazines for empty tubes and full cops does not have to be accelerated and braked again at each step of operation.

In one of the cop doffing apparatus which has become known, and which travels along the machine at constant speed, the cops are forced off the spindles by a lifting wedge (German Patent 1,111,075). In this case, however, there exists the danger of exerting a tilting stress on the spindle bearings and of distorting them, which can happen especially when a cop is set somewhat more tightly than usual on the spindle. Damage can furthermore be caused to the tubes or to the yarn by the lifting wedge. Another disadvantage of this doffing method consists in the fact that it cannot be used on spinning machines with balloon narrowing rings.

Another cop doffing apparatus moving along the machine at constant speed has become known (U.S. Patent 3,070,949), which doffs the cops successively, one by one, by means of a grasping device; the cops are seized at their lower end by a rotating gripper during the travel of the cop doffer, and are twisted from the spindle. This apparatus has the disadvantage that the cop tubes have to be especially constructed at the bottom end so as to provide a place for the gripper to grasp it. Furthermore, such a cop doffing apparatus can be used only on machines without balloon narrowing rings.

These disadvantages which occur in cop changers of the prior art are eliminated in the use of the present invention by the fact that while the carriage is moved at constant speed, a movement relative to the carriage is

2

imparted to the gripper disposed on the carriage and seizing the individual cops at their upper end, so that, during its doffing movement, the gripper is temporarily substantially motionless with reference to the spindle being stripped and the direction of movement of the carriage. The movement of the gripper relatively to the advancing movement of the carriage can be produced by a horizontal swinging movement of the gripper, which simultaneously serves to cover the distance between the spindle being stripped and the point at which the cops are discharged. The swinging movement of the gripper can be a rocking movement limited to the sector between the discharge point and the spindle, or it can be a rotational movement wherein the gripper moves from the discharge point to the spindle and back again to the discharge point, without reversal of the direction of movement. The movement, however, can also take place in such a manner that the necessary relative movement between gripper and carriage is produced by a vertical swinging movement which simultaneously draws the cop from the spindle. Likewise, according to the invention, a relative movement can be imparted to the means disposed on the carriage for feeding empty cops to the spindles, so that the feed means is temporarily substantially motionless during the cop placement, with reference to the spindle being supplied, while the carriage continues to advance. The cop, following such placement on the spindle, can be pushed down to the in-place or loaded position by a pressure roller which likewise receives a movement relatively to the carriage, so that it is substantially motionless during the pressing movement, with reference to the spindle and the direction of movement of the carriage, while the carriage continues to advance.

One special advantage of the method of the invention consists in that the cops are seized at their apex in such a manner that neither the tubes nor the yarn wound thereon can be damaged. Furthermore, the cop changer of the invention can be installed on machines equipped with as many balloon narrowing rings as desired, due to the special design of the gripper.

Thus, the invention provides apparatus for use in the manipulation of a cop with respect to a spindle therefor. The apparatus includes a carriage, means for moving the carriage over a path going past the spindle at a constant speed with respect to the spindle, and cop moving means movably mounted on the carriage and adapted for facilitating the carrying out of the manipulation as the carriage passes the spindle. The cop moving means includes an engaging member for engaging the cop. Means are provided for moving the cop moving means relative to the carriage to impart to the engaging member movement thereof opposite of the movement of the carriage to substantially eliminate relative movement of the engaging means and the spindle in the direction of movement of the carriage, during the manipulation.

The movement of the engaging member to substantially eliminate relative movement, as aforesaid, is for the purpose of facilitating the removal of a filled cop, and such movement is in addition to the movement provided for effecting the removal of the filled cop. In general, the removal movement is a lifting movement to lift the filled cop from the spindle. Thus, the apparatus of the invention includes a first mover means for moving the cop gripping means to move a filled cop engaged by the gripping means engaging member, axially of the spindle for removal of the filled cop from the spindle, and second mover means to move the cop engaging means opposite the movement of the carriage to eliminate relative movement of the engaging member and the spindle, as aforesaid, while the engaging member is in engagement with the filled cop and until removal of the cop from its spindle.

The invention is further described in the accompanying drawing, wherein:

FIG. 1 is an elevation view of a carriage according to the invention, showing the carriage disposed in front of a device having spindles and in combination with which the carriage of the invention can be used;

FIG. 1a is a view taken along line 1a-1a in FIG. 1, showing the magazine for the cops, and showing the conveyor schematically;

FIG. 2 is a cross-sectional view taken along line 2-2 of FIG. 1, but showing the gripper 7 in FIG. 1 in a different position from that shown in FIG. 1, to better illustrate the device;

FIG. 3 is a view, partially in cross-section, of a gripper for the apparatus of the invention;

FIG. 4 is a view of a part of the gripper shown in FIG. 3, showing the operating parts of the gripper in a different position;

FIG. 5 and FIG. 6 show, respectively, alternative constructions for the gripper;

FIG. 7 is a view of a portion of the apparatus shown in FIG. 1, taken along line 7-7 in FIG. 1;

FIG. 8 is a top plan view of the part of the apparatus shown in FIG. 7;

FIG. 9 is a side elevation view taken along line 9-9 in FIG. 8;

FIG. 10 is a schematic representation of the gripper utilized in the apparatus shown in FIG. 1, and further indicating the manner of operation of the gripper, whereby relative movement between the gripper engaging member and the spindle is eliminated;

FIG. 11 is a schematic representation of a gripper, in top plan view, of alternative construction and operation to that for the apparatus of FIG. 1;

FIG. 12 is a schematic representation indicating an alternative means to that utilized in the apparatus of FIG. 1, for eliminating relative movement between the gripper engaging member and the spindle, in the direction of movement of the carriage;

FIG. 13 is a schematic plan view indicating a construction for a carriage alternative to that shown in FIG. 1;

FIG. 14 is a partial cross-sectional view taken along line 14-14 in FIG. 13; and

FIG. 15 is a partial cross-sectional view taken along line 15-15 in FIG. 13.

In the various views of the drawings, like reference characters indicate corresponding parts.

The carriage 1 is resiliently mounted on wheels 4 and is provided with wheel 29 which rolls on the track 2 secured to the spinning machine 1a. The lower side of rail 2 is cut to provide a rack 5 for engagement by pinion 6 of the carriage 1. The spinning machine also has a guide rail 3 on which the wheel 28 of the carriage rides.

Carriage 1 is provided with an engaging member or seizing element 8 disposed on a gripper 7. See FIG. 3 and FIG. 4. The seizing element 8 is actuated, for example, by an electromagnet 10 through a two-armed lever 9. The gripper 7 is connected through a push rod 11 and crosshead 12 with a pair of push rods 13 and 13'. The push rods 13 and 13' are mounted at their lower extremity on the crank pin 14 of crank 15. The crankshaft 16 is driven by the motor 20 (FIG. 1) through a gearing including motor driven sprocket wheel 19 and idler sprocket 17, and chain 18. The push rod 11 is rotatable in the crosshead 12 and is secured thereto for vertically directed movement therewith. Any suitable known connection (not shown) between push rod 11 and crosshead 12 can be used, e.g. a horizontal tongue and groove connection. The push rod 11 is slidably received in a circular opening in guide plate 13a and the push rods 13 and 13' pass through appropriate slots in the guide plate.

A cam 21 is fastened on the crankshaft 16 and works upon shaft 24 through cam follower roll 22 and a one-armed lever 23. Two holders 25, which hold a rod 26, are

fixedly secured by set screws 25' to the shaft 24. Rod 26 is straddled by a rocker fork 27 rigidly affixed to the push rod 11 by set screw 27'.

The crank pin 14 travels in a circular path around the crankshaft 16 by means of crank 15. The push rods 13, 13' are rotatably positioned at their lower end, on the crank pin 14, and at their upper ends, on crosshead 12. The fork 27 is rigidly affixed to the push rod 11. Thus the crosshead 12 (in which the push rod 11 is rotatably positioned) is pushed against fork 27, whereby the push rod 11 with gripper 7 is pushed upward. This results in the upward and downward movement of the gripper 7 (i.e. the vertical doffing movement over the spindle 53). The gripper 7, however, must simultaneously make a swinging movement for discharge of the filled cop 30 or placement of the empty cop on the spindle, respectively. This swinging movement is initiated by the cam 21, which is rigidly connected with crankshaft 16. Thus through the cam 21 over the roll 22 and the lever 23, the shaft 24 is rocked. Through this turning movement, the rod 26 (fixedly secured to the shaft 24 by means of holders 25) is also moved to and fro. Rod 26 is straddled by a rocker fork 27 rigidly affixed to the push rod 11. Thereby the turning movement of the shaft 24 is transferred to the push rod 11 (FIG. 2). The rod 11 moves up and down, and is simultaneously rocked or turned to and fro by the fork 27.

To handle the filled cops 30, there is located on the carriage 1 a discharge hopper 31 (FIG. 1), a conveyor chain 33 driven by a chain sprocket 32 and chain 18, and a cop collector 34. The cop collector 34 consists substantially of a gathering band 35 approximately matching in width the length of the cops 30, which can be wound onto the shaft 36, driven by appropriate means.

The empty cops 37 are contained in a magazine 38 and are withdrawn therefrom and fed to the spindle loading device by conveyor 39. The magazine 38 is removably mounted on carriage 1.

Referring to FIG. 1 and FIG. 1a, the magazine 38 is mounted in the carriage with its bottom inclined providing gravity feed to the bottom edge corner 38b, and it has a downwardly depending partition 38a disposed parallel to said bottom edge corner and terminating short of the bottom of the magazine a distance such that cops can pass under the partition. The partition provides the loading section 38c and the holding section 38d and is spaced from the walls of the magazine which are parallel thereto, a distance less than the length of the cops so that cops cannot work into a position in which they are disposed perpendicular to the flights 39a of the conveyor 39. Further, by reason of the positioning of the partition and the inclined attitude of the magazine when in place on the conveyor, the cops will work to position wherein they are parallel to the flights 39a. Thus a cop as is shown in FIG. 1a, in the section to the right of the partition will work to a position as is shown for the cops on the left of the partition. The flights 39a are constructed and spaced so that there is room for but one cop between next adjacent flights.

The pre-sorted tubes 37 automatically feed themselves between the cleats 39' of the conveyor chain 39 (FIG. 8), due to the inclination of the magazine 38. The spindle loading device consists of a chute 40 into which the tubes are dropped onto a deflector 41 (FIG. 7) by which the tubes are guided into a tube holder 42, so that they are standing on their wider ends in the holder 42. Such positioning of the tubes is assured by taking care to position the tubes in the magazine with their wider ends adjacent each other and with all wider ends disposed in a manner corresponding to the deposit of the tubes in the holder 42 with wider ends down. The desired positioning of the tubes is maintained in their travel from the magazine 38 to the holder 42. The tube holder 42 is pivotingly mounted in the two bearings 43 and 44 (FIG. 7), and is moved through the fork 45 by a pin 46 fixedly fastened

to the pusher 60. Underneath the tube holder 42 there is disposed an immovable holder 48 whose standing surface is coplanar with the tube standing surface 47 of the tube holder 42. The tube holder 42 is additionally provided with two springs 50 to hold back the tubes 37. Pusher 60 is fixedly secured to shaft pin 61 (FIG. 8 and FIG. 9) and a one-armed lever 72 with a cam follower 71. The cam follower 71 runs on the track 70 of a cam 69 fastened on shaft 73. The pin 61 is journaled in journal blocks 61a, 61b. The carriage is provided with an opening 61c, through which the lever 72 can be seen. The cam 69 serves simultaneously as a crank for the push rod 68. Push rod 68 is connected through an articulation 67 to a one-armed lever 52. An elastic roller 51 is provided on the one-armed lever 52 pivoting about the pin 54 so as to press the tubes 37 onto the spindles 53.

The movement of the pusher 60, pushes the tubes 37 into the holder 42, and the movement of the holder 42 serves to move the holder so that the outermost tube in the holder drops onto a spindle 53. The roller 51 then pushes the tubes home on the spindle 53. The movement of pusher 60 is effected by its shaft pin 61 (FIG. 9), which is connected with the one-armed lever 72, and the lever 72 in turn is connected with cam follower 71. This cam follower 71 runs on the track 70 of the cam 69 and, as described above, transfers the movement of the cam follower 71 to the pusher 60. On this pusher 60 there is affixed the pin 46 which moves the tube holder 42 to and fro by means of the fork 45 in which pin 46 is received. The cam 69 also actuates the lever 52, through the push rod 68, so that the tubes 37 are pressed home on the spindles 53 by the roller 51.

The cop doffing machine described here in detail is so constructed that it can be used on all spinning machines of equal division (spindle spacing) and cop tube length, which are equipped with the corresponding carriage rails 2 and guide rails 3. Accordingly, a single cop doffing machine can be used for any desired number of spinning machines. Nevertheless, it is also possible to associate a separate cop doffing machine with each side of a ring spinning machine. If a cop doffing machine is to be used on a plurality of ring spinning machines, and appropriate safety device must be provided for engaging and disengaging, so that the working movements of the cop doffing machine coincide precisely in each case with the spindle spacing in the spinning machine. This safety device may consist, for example, of a larger tooth in the rack 5 on carriage rail 2 and a corresponding gap in the pinion 6. Also, a cam can be mounted laterally on pinion 6 to cooperate with a corresponding stop pin disposed on carriage rail 2.

The electrical motor 20 is supplied with power by means of a "third rail" which is not shown, or by means of a flexible cable.

As soon as the ring spinning machine stops when the cops are full, the cop doffing machine is started, which can be brought about automatically by the spinning machine after the wind-under, through the use of appropriate means, or else manually by the operator. When the motor 20 of the cop doffing machine is turned on, the carriage 1, and with it the gripper 7 and seizing element or insert 8 mounted thereon, moves at constant speed in the direction of arrow P_1 past the spindles 53 of the spinning machine. The gripper 7 is at the same time so driven that, in spite of the uniform traveling speed of carriage 1, a vertical doffing movement is produced above the spindles 53. As it appears from FIGS. 1-10, the carriage 1 is moved continuously in the direction of the arrow P_1 , whereupon the gripper 7 with the seizing element 8 is swung by the cam 21 and the corresponding parts 22 through 27 from the filled cop discharge position A into position S above spindle 53. See FIG. 10. At the discharge position A the filled cops are released to the hopper 31 (FIG. 1). While the carriage 1, and hence

also the pivot point L of gripper 7, moves steadily on the point L', the gripper 7 is pivoted about the angle α in such a manner that the seizing element 8 stands still (with respect to the direction of movement of the carriage 1) at spindle 53 while carriage 1 continues to move onward. This relative standstill of the seizing element 8 above the apex of the spindle lasts for a fraction of a revolution of the crankshaft 16 (FIG. 2), during which time the gripper 7 is lowered and then raised again with the cop. As soon as the seizing element 8 has been introduced, at the bottom dead center of the rising and falling movement, into the upper part of the cop 30 where it extends somewhat above the top of the spindle, the electromagnet 10 is energized (FIG. 3). In this manner the connecting rod 58 is moved in the direction of the arrow P_2 , whereupon the two-armed lever 9 performs a corresponding pivoting movement about its pivot point 59. The ring 57 on bolt 55 is forced downward and the seizing element 8, which consists of a resilient or elastic material, is squeezed between the ring 57 and the end plate 56 of bolt 55 (FIGS. 3 and 4). The seizing element 8 thereupon increases its circumference and tightly seizes the cop 30.

After the cop 30 has been pulled from the spindle by the movement of crank 15 (FIG. 1), the push rod 11 is swung back by cam 21 and the corresponding members 22 through 27, until the gripper 7, with the cop hanging from it, is located over the discharge hopper 31 (position A in FIG. 10). The electromagnet 10 is de-energized by an appropriate switch, which is not shown, whereupon the cop 30 is dropped into the discharge hopper 31. The full cops are guided to a horizontal position in the discharge hopper 31 and are directed to the conveyor chain 33, which injects them into the gathering band 35 of the cop collector 34.

The pivoting (turning) movement of the shaft 24 is provided by the cam 21, the cam follower roll 22, and lever 23. A switch (not shown) is switched on and off by this cam 21. The electromagnet 10 is connected with the switch and is either switched on (the electromagnet moves the connecting rod 58 in the direction of the arrow P_2 , the two-armed lever 9 thus effects a pivoting movement around its fulcrum 59, expands the gripper 8 and clamps the cop 30) or switched off (electromagnet de-energized; connecting rod 58 moves opposite to the direction of the arrow P_2 , thus effecting the reverse pivoting movement of the lever 9 around its fulcrum 59, whereby the gripper 8 releases its grip on cop 30 so that the cop is dropped into discharge hopper 31).

Thus, the apparatus includes for the doffing of the filled cops a first mover means in the form of the crank 15, and the parts interconnecting this crank with the pusher rod 11, for reciprocating the gripper 7 in the direction of the axes of the spindles, and a motion provided by this first mover means serves to effect the lifting of the filled cop from its spindle. The apparatus further includes a second mover means, in the form of the cam 21 and the parts associated therewith for imparting rotational movement to the push rod 11, for moving the gripper 7 in a direction transverse to the axes of the spindles. This movement transverse to the axes of the spindles provides elimination of relative movement of the engaging means in the form of the plug 8 (FIG. 4), and the spindle 53, in the direction of movement of the carriage 1.

Referring again to FIG. 10, the above-stated second mover means serves to move the gripper 7 pivotally about axis L which is parallel to the axes of the spindles, through a backstroke, wherein the gripper is moved so that the engaging member 8 thereof is past through the angle α from S to S', and during this backstroke, relative movement, as aforesaid, is eliminated. Further, this second mover means serves to move the gripper 7 through a forward stroke wherein the engaging member, now with a filled cop engaged thereby and in a raised position

wherein the bottom of the filled cop is above the top of the spindles, from position S to S'. The movements of the gripper include not only the reciprocating movement, wherein the lifting of filled cops from the spindles is effected, and the described movement transverse to the spindle axes, whereby the relative movement is eliminated, but in addition, a third movement is provided. Thus, a third mover means is provided to effect movement of the gripper so as to carry a filled cop engaged by the gripper to a position over the hopper 31 (FIG. 1), and the filled cop is then released from the gripper 7 so that it falls into the hopper 31. This movement can be provided by extending the arc between points S-S', so that on the forward stroke of the gripper, the engaging means end of the gripper is swung to a position such that a cop held thereby will be over the hopper 31. This movement of the gripper beyond the arc S-S' can be provided by suitably designing the cam 21, so as to provide the desired stroke for the gripper 7. Desirably, the hopper or receiver 31 is positioned for receiving the filled cops at the end of or during the forward stroke of the gripper.

The empty cops 37 are carried by conveyor chain 39 from the magazine 38 into the chute 40 (FIGS. 7 and 8). The cops 37 slide over the deflector plate 41 into the tube holder 42, while at the same time they are stood up with their wider ends down, in the ready position.

An appropriate sensing means can be provided to check the position of the tubes and shut the cop doffing off immediately, as soon as the large diameter of a tube is accidentally at the wrong end. Another sensing means can be located in front of the tube setting mechanism to shut off the doffing machine if an empty tube or full cop is still on the spindle being served. When the holder 48 (FIGS. 7 and 8), as a result of the continuous advancement of carriage 1, moves over an empty spindle 53, the tube holder 42 with the tubes standing therein is swung by the cam 69 (FIG. 9) to move the empty cop which is disposed at the discharge end of the holder 42, as is indicated in FIG. 8, from the rest or stand plate 49, so that this empty cop drops onto the spindle which at this moment is in a position to receive the empty cop. At the same time the empty cop 37 is moved in a direction opposite to the direction of movement of carriage 1 in such a manner that as it falls onto the spindle it is moved transverse to the spindle axis so that relative movement between empty cop and spindle in the direction of travel of the carriage 1, is eliminated. Simultaneously, the conveyor chain 39 throws a fresh cop tube 37 into the chute 40. This tube slides over the deflector 41 and falls with its wide end down, in front of the retracted pusher 60. Pusher 60 is thereupon moved forward again by the cam 69, thereby swinging tube holder 42 back to its starting position by means of pin 46, and at the same time pushing the tube that has fallen down over deflector 41 into the tube holder 42. When the tube holder has reached the position shown in dash-dotted lines in FIG. 8, the foremost cop tube has been pushed from the standing surface 47 of tube holder 42 onto the stand plate 49 of holder 48. The springs 50 hold the next two cop tubes steady and secure them against accidentally falling when the tube holder 42 swings.

Thus, the apparatus includes empty cop manipulating means which is mounted on the carriage for manipulation of empty cops during a single passage of the carrier over its path, to place empty cops on spindles from which filled cops have been removed during the same single passage over the path of the carriage. The manipulating means effects placement of an empty cop on a spindle by movement of the cop axially of the spindle into the cop loaded position. The manipulating means includes an empty cop mover, in the form of cam 69 and the linkage of this cam to the holder 42, for moving the empty cop opposite the movement of the carriage to eliminate relative movement, in the direction of move-

ment of the carriage, of the empty cop and the spindle on which it is placed during movement of the empty cop axially of the spindle.

The cop that moves by free fall down from the holder 48 onto spindle 53 is pressed onto the spindle by the roller 51 mounted on lever 52. See FIGS. 8 and 9. The pin 54 about which the one-armed lever 52 pivots is so disposed that the roller 51, in its downward movement, simultaneously moves contrary to the direction of movement of carriage 1, whereby it is substantially at a standstill relatively to the spindle axis in the moment in which it presses down to cop tube.

When all the spindles on the spinning machine have been served with cop tubes in the manner described above, the cop doffing machine is run back to its starting position. To this end, a clutch on shaft 65 is operated by manual lever 66, thereby shutting off the driving of chain 18 and reversing the gearing that controls pinion 6. The reverse movement is designed as a rapid movement, so that the cop doffing machine can be returned to the starting position in a minimum of time. The return of the cop doffing machine to the starting point can also be started automatically by an appropriate stop at the end of the spinning machine. When the cop doffing machine has reached the end of the spinning machine, it is also possible to disengage it from carriage rail 2 and supporting rail 3 and, rolling it only on wheels 4, to bring it to the next spinning machine.

The cops are taken from the cop doffing machine together with the gathering band and tied into a bundle or put into a container. After the cops have been removed from the doffing machine, a gathering band 35 must again be wound onto shaft 36. The magazine 38 which has been emptied in the spindle serving operation is replaced manually with a fresh container full of previously sorted cop tubes.

Additional examples of embodiments for the gripper for stripping the spindles are represented in FIGS. 5 and 6. In the case of the gripper 7 shown in FIG. 5, the upper portion of the cop 30 being removed is seized externally, the elastic seizing element or socket 8' diminishing its inside diameter in order to produce a seizing action. To this end, an appropriate device such as an electromagnet 10 as shown in FIG. 3 pivots the two-armed lever 9 about its fulcrum 59 so that it forces the pressure plate 57' downward, whereupon the seizing element 8' is squeezed between the pressure plate 57' and the base plate 57'', thereby reducing the inside diameter of the hole which is pushed over the apex of the cop tube. In the embodiment shown in FIG. 6, the seizing element or socket of gripper 7 consists of a noose 8'' which is tightened by an appropriate means in the direction of the arrow P₃, in order to bring about the seizure of the apex of the cop tube. The noose is guided in a groove on the entire circumference of the cop tube.

FIG. 11 shows an alternative construction for the gripper for doffing the cops, wherein the gripping means includes a plurality of engaging members. Three individual grippers 7', 7'' and 7''' are combined into a single star-shaped gripper. The three grippers combined do not perform a back-and-forth movement, but are rotated continuously in the direction of the arrow P₄. In this embodiment, the transmission (not shown) between the crank-shaft 16 and the rotation of the push rod 11 can be by gearing or chain and must be chosen corresponding to the number of grippers, so that per stroke of the push rod 11 imparted by the crank 15, the push rod 11 executes a fraction of one revolution equal to the reciprocal of the number of grippers 7: for three grippers, $\frac{1}{3}$ revolution and a transmission ratio from the shaft 16 of 3 to 1. Every time one of the grippers 7', 7'', 7''' is above the spindle to be drawn off, it is lowered, analogously to the above described execution according to FIGS. 1, 2 and 10, and again raised with the full cop. During this down movement and again up movement the push rod 11 continuously

goes on rotating the angle α , so that, for example the gripper 7", as shown in FIG. 11, stands relatively still to the spindle during the drawing off movement. After drawing off of the cop, the push rod 11 continues to turn continually in the direction of the arrow P₄. When the next gripper 7' is lowered over the next spindle, simultaneously with this lowering movement, the cop of the gripper 7", or 7'", is discharged when it is swung over the full cop receiving hopper 31 (FIG. 1). Otherwise, the machine is the same as is set forth in the preceding description.

Another possibility for moving a gripper from a carriage traveling at constant speed in such a manner that it stands still, in the direction of movement of the carriage 1, momentarily, relative to the spindle of the cop being doffed, is indicated schematically in FIG. 12. The pivot point A of lever C is fastened to the carriage 1 and moves with the latter in the direction of the arrow P₁. Point B represents the point at which the element for seizing the cops is disposed. If the carriage 1 moves uniformly in the direction of the arrow P₁, so that the pivot point A of lever C is displaced to A', lever C can simultaneously be swung upward by the angle α' in such a manner that point B performs a doffing movement substantially vertically upward, in line with the spindle axis, to point B'.

The lever C corresponds to the gripper 7. Point B signifies the place, at which is positioned the gripper (not shown) corresponding to the gripper 8 (FIG. 3). The drive for lever C can be as is shown in FIG. 9 for the lever 52 utilized in loading on of empty spools. However, the up and down movement of the lever C may also be imparted by an arm driven from a cam disc, which is, for example, linked to the lever C, at the point D. In order to attain a discharge of the full cop into the receiver 31, on the carriage 1, the lever C undergoes, through a buffer (not shown) or by a slight slanting position of its swivel axis at point A, a slight lateral deviation. The point B is then no longer precisely above the spindles 53, and it is above the receiver 31 on the carriage 1, and is then discharged. In this embodiment, cam disc 21 (FIG. 2) is not used. In all other details, the machine corresponds to the previously described embodiment of FIG. 1.

In the embodiment shown in FIGS. 13, 14 and 15 of a cop changing apparatus of the invention, gripper 8''' for doffing the cops is not swung, but is displaced with a slide 79, by appropriate means, during the doffing and the cop tube serving operation, in the direction of arrow P₅, contrarywise to the direction of movement of carriage 1, and it returns again after the said doffing and cop tube serving operation.

The movement of the slide 79 in the direction of the arrow P₅ is effected by gear 80 and rack 81. The gear 80 is driven, via gearing (not shown) from the crankshaft 16 (FIG. 2). For the movement of the slide 79 opposite to the direction of the arrow P₅, the rack 81 is disengaged from gear 80 by, for example, providing a portion of gear 80 free of teeth. Upon the disengagement, the return movement of the slide 79 can take place through the action of a tension spring. Alternatively, the drive of the slide 79 may be effected through an appropriate crank mechanism, or through pneumatically or hydraulically operated pistons, wherein for the return movement a spring or a piston with counter pressure is used. The drive takes place in synchronism with the operation of gripper 8''' controlled by the push rod 11, as shown in FIG. 2. Thus the slide 79 can execute during the drawing off movement a corresponding movement with respect to carriage 1, providing the desired zero relative motion. The gripper 8''' after the drawing off, is disposed over the catcher 74. The crosshead 12 (FIG. 2) must be provided with a slot so that the push rod 11 can follow the slide movement of the slide 79.

The gripper 8''' drops the removed cop 30 into a catcher 74 from which it can be fed to a gatherer by a

conveyor chain in the manner previously described. The cop tube feeding chute 40' with the pusher 60' operates in a manner similar to the embodiment in FIG. 1, but the necessity for swinging, as in the case of the holder 42 (FIG. 8), is eliminated. The cop tube 37 is dropped through the guide 77 fastened to slide 79, down from the standing surface 78, onto the spindle 53, and can be pressed onto the spindle in the manner already described.

In the embodiments of FIGS. 10 and 11, the gripper is pivoted to provide the transverse movement; in the embodiment of FIG. 13, it is moved linearly.

In the embodiment of FIG. 14, the lifting of the engaging member and moving the engaging member to provide the zero relative motion, is effected simultaneously by the one mover means which moves the engaging member in a vertical plane.

While the invention has been described with respect to particularly embodiments thereof, these embodiments are merely representative, and do not serve to set forth the limits of the invention.

What is claimed is:

1. Apparatus for use in lifting a cop off an upright spindle comprising a carriage; means for moving said carriage over a path going past the spindle at a constant speed with respect to the spindle, cop moving means movably mounted on the carriage for lifting the cop as the carriage passes the spindle, said cop moving means including an engaging member for engaging the top portion of the cop for said lifting, and means for moving the cop moving means relative to the carriage to impart to the engaging member movement thereof opposite the movement of the carriage to substantially eliminate relative movement of the engaging means and the spindle in the direction of movement of the carriage, during said manipulation.

2. Apparatus for removing filled cops from spindles therefor comprising:

- (a) a carriage;
- (b) means for moving the carriage over a path going past the spindles one at a time and at a constant speed with respect to the spindles,
- (c) cop gripping means including a cop engaging member movably mounted on the carriage for gripping each filled cop as the carriage passes the filled cop,
- (d) first mover means for moving the cop gripping means to move a filled cop engaged by the gripping means engaging member axially of a spindle for removal of the filled cop from the spindle,
- (e) and second mover means to move the cop engaging means opposite the movement of the carriage to eliminate relative movement of the cop engaging member and the spindle in the direction of movement of the carriage while the engaging member is in engagement with the filled cop until removal of the cop from its spindle.

3. Apparatus according to claim 2, wherein the first mover means reciprocates the gripping means in the direction of the axes of the spindles, and the second mover means moves the gripping means in a direction transverse to the axes of the spindles to provide said elimination of relative movement.

4. Apparatus according to claim 3, and including a receiver for doffed filled cops, said receiver being mounted on the carriage and spaced from the spindles, third mover means for moving the cop gripping means while the cop gripping means are engaged with a filled cop removed from its spindle, for delivery of the filled cop to the filled cop receiver.

5. Apparatus according to claim 3, wherein the second mover means pivots the gripping means about an axis fixed with respect to the carriage and parallel to the spindle axis, the second mover means pivoting the gripping means to rock the gripping means through a backstroke during which the relative movement of the gripping means

engagement member and the filled cop is eliminated as aforesaid, and a forward stroke during which the gripping means is returned for engagement of the engagement member with the next adjacent filled cop along the path of the carriage.

6. Apparatus according to claim 5, and including a receiver for removed filled cops, said receiver being mounted on the carriage spaced from the spindles, said receiver being positioned to receive a filled cop from said gripping means during one of said strokes upon release of the filled cop by the engagement member, and means for effecting said release for delivery of the filled cop to the receiver.

7. Apparatus according to claim 5, and including a receiver for removed filled cops, said receiver being mounted on the carriage spaced from the spindles, said engagement member during said rocking moving over an arc relative to the carriage defined at one end thereof by the position of the engagement member upon initial engagement of a filled cop and at the other end by the position of the engagement member at the time of removal of the filled cop from its spindle, said receiver being disposed along an extension of said arc, said strokes of the gripping means extending along a corresponding extension of said arc for delivery of filled cops to the receiver.

8. Apparatus according to claim 7, wherein the receiver is disposed for receiving filled cops during said forward stroke.

9. Apparatus according to claim 3, wherein the second means pivots the gripping means to provide said transverse movement.

10. Apparatus according to claim 3, wherein the second mover means moves the gripping means linearly to provide said transverse movement.

11. Apparatus according to claim 2, the second mover means moves the gripping means in a direction transverse to the axes of the spindles to provide said elimination of relative movement.

12. Apparatus according to claim 11, wherein the second mover means rotates the gripping means about an axis fixed with respect to the carriage and parallel to the spindle axes, to move the gripping means engaging member into position for engagement of a filled cop, thereafter to move the engaging member to eliminate said relative movement as aforesaid, and after said removal of the cop from its spindle to return the engaging member to said position for engagement of a filled cop, a receiver for filled cops on said carriage spaced from the spindle and disposed along the path of the engaging means as it moves from the time of removal of the cop from its spindle to said position for engagement of a filled cop, and means for releasing a filled cop from the engaging means for delivery thereof to said receiver.

13. Apparatus according to claim 2, and including a receiver for doffed filled cops, said receiver being spaced from the spindles, and third mover means for moving the cop gripping means while engaged with a filled cop removed from its spindle for delivery of the filled cop to the filled cop receiver.

14. Apparatus according to claim 13, said receiver being mounted on the carriage.

15. Apparatus according to claim 2, and empty cop manipulating means mounted on the carriage for manipulating empty cops during a single passage of the carrier over said path to place empty cops on spindles from which spindles, filled cops have been removed during said single passage.

16. Apparatus according to claim 15, said manipulating means effecting placement of each empty cop on a spindle by movement of the cop axially of the spindle into the cop loaded position, and including an empty cop mover means for moving the empty cop opposite the movement of the carriage to eliminate relative movement, in the direction of movement of the carriage, of the

empty cop and the spindle on which it is placed during movement of the empty cop axially of the spindle.

17. Apparatus according to claim 16, and further including empty cop presser means for pushing the cop axially of the spindle during said movement of the cop axially of the spindle, and mover means for the presser means for moving the presser means opposite the movement of the carriage to eliminate relative movement, in the direction of relative movement of the carriage, of the presser means and the spindle in which it is placed during movement of the empty cop axially of the spindle.

18. Apparatus according to claim 15, said manipulating means effecting placement of each empty cop on a spindle by movement of the cop axially of the spindle into the cop loaded position, and further including empty cop presser means for pushing the cop axially of the spindle during said movement of the cop axially of the spindle; and mover means for the presser means for moving the presser means opposite the movement of the carriage to eliminate relative movement, in the direction of relative movement of the carriage, of the presser means and the spindle on which it is placed during movement of the empty cop axially of the spindle.

19. Apparatus according to claim 15, said manipulating means including means for dropping empty cops onto spindles disposed vertically for free falling of the empty cops onto the spindles.

20. Apparatus according to claim 15, said spindles being disposed vertically and for removal and placement of cops from the top thereof, said empty cop manipulating means comprising a holder disposed above the spindles for holding an empty spindle in upright position above the spindles and having a spindle receiving end and a spindle discharge end, a rest disposed above the spindles and for receiving a spindle from the holder discharge end, said rest being fixedly positioned on said carriage and disposed for supporting empty cops received from the holder over the spindles, and means for moving an empty cop from the holder discharge end to the rest, and means for pushing an empty cop from said rest for falling thereof onto a spindle.

21. Apparatus according to claim 20, a magazine for empty cops mounted on said carriage, said magazine having a delivery opening disposed for issuing empty cops from the magazine, a conveyor for receiving empty cops issued by the magazine and carrying the empty cops one at a time at a fixed rate to a level disposed above the holder and dropping the empty cops from said level, a guideway for receiving empty cops dropped by the conveyor and delivering them to said holder receiving end in upright position for dropping onto a spindle, and a pusher for pushing the empty cops through said holder from the receiving end to the delivery end thereof.

22. Apparatus according to claim 15, and including a magazine for empty cops, a conveyor for withdrawing cops from the magazine and delivering them to the manipulating means, said magazine comprising a container mounted on the carriage with its bottom inclined to the horizontal to gravity feed cops within the container to a bottom edge corner of the container, means defining an opening in said bottom edge corner for entry of conveyor elements for the withdrawal by the conveyor, a depending partition disposed in the container parallel to said bottom edge corner and terminating short of the bottom, said partition dividing the container to provide a cop loading section which includes said bottom edge corner and a cop holding section, a plurality of cops in the holding section, the dimension of each of said sections perpendicular to partition being less than the length of the cops.

23. Apparatus according to claim 2, said first mover means comprising a reciprocating member directly connected to the gripping member and for imparting reciprocation to the gripping means in the direction of the spindle axes, said second mover means comprising a

rocker for turning said reciprocating member in a direction transverse to the axes of the spindles to thereby turn the gripping member in a direction transverse to the spindle axes, and a cam follower, said apparatus further comprising a crank shaft and a crank connecting rod connected to said reciprocating member, and a cam mounted on said shaft for driving the cam follower and imparting a rocking motion to said rocker.

24. Apparatus according to claim 2, the gripping means comprising an arm having said engaging member disposed adjacent one end thereof, said engaging member comprising an insert for insertion to the end of a hollow cop, and being expandible to permit it to grip the inside surface of the cop following said insertion, and means for expanding the insert following insertion thereof into a cop.

25. Apparatus according to claim 2, gripping means comprising an arm having the said engaging member disposed adjacent one end thereof, said engaging member comprising a socket for disposition with the end of a hollow cop received therein, said socket being contractible to permit it to grip the outside surface of the cop following receipt of the cop therein, and means for contracting the socket following receipt of the cop.

26. Apparatus according to claim 2, the gripping means comprising a plurality of engaging members as aforesaid.

27. Apparatus for use in lifting a cop off an upright

5 spindle comprising a carriage, means for moving said carriage over a path going past the spindle at a constant speed with respect to the spindle, cop moving means movably mounted on the carriage for lifting the cop as the carriage passes the spindle, said cop moving means including an engaging member for engaging the top portion of the cop, said cop moving means simultaneously lifting the engaging member for lifting the cop off its spindle and moving the engaging member opposite the movement of the carriage to substantially eliminate relative movement of the engaging member and the spindle in the direction of movement of the carriage, during said manipulation.

28. Apparatus according to claim 27, the moving means pivoting the engaging member in a vertical plane during said lifting of the cop.
